UNITED STATES PATENT OFFICE.

HENRY A. ZIOLA, OF TOLEDO, OHIO, ASSIGNOR TO THE SWARTZBAUGH MANUFACTURING COMPANY, OF TOLEDO, OHIO, A CORPORATION.

ELECTRIC TERMINAL CONSTRUCTION.

Application filed May 20, 1926. Serial No. 110 497

The present invention relates to an electric terminal construction, and has for its object to provide a device of this character which is inexpensive in its construction and can be used in connection with any form of electrical tool or appliance where a plug and socket connection is desired.

Further objects of the invention are to provide a device of this character which can be manufactured very economically, which can be readily applied to any form of electrically heated or operated device, and which provides a quick and effective means for making or breaking the electrical connection.

While one particular embodiment of the invention is shown and described in this application for illustrative purposes it will be understood that many modifications and changes can be made without departing from the spirit of the invention.

For a full understanding of the invention reference is to be had to the following description and accompanying drawings, in which

Figure 1 is a front elevation of a plate having one of the terminal sockets mounted thereon.

Figure 2 is a horizontal sectional view on the line 2—2 of Figure 1, looking in the direction of the arrows.

Figure 3 is a horizontal sectional view through the device on the line 3—3 of Figure 1.

Figure 4 is a rear view of the device.

Corresponding and like parts are referred to in the following description and indicated on all of the views of the drawing by like reference characters.

Referring to the drawings, the reference character A designates an elongated socket into which a set of terminal pins 1 project. The terminal pins are carried by a block 2 of lava or other insulating material which is secured to the socket at the back thereof. The rear ends of the terminal pins extend through openings in the lava block 2 and are threaded to receive the nuts 3. Shoulders or nuts 4 which are applied to the terminal pins engage the front of the lava block and are clamped against the same by tightening the nuts 3. The electric wires of the circuit or circuits are connected to the rear ends of the terminal pins 1.

The elongated socket A is formed of two complementary sections 5—5 which are similar and interchangeable in construction.

Each of the socket sections 3 includes a substantially flat middle portion 5^a and end wings 5^b which are curved laterally, one of the end wings being formed with an off-set flange 5^c. When the two socket sections are assembled from opposite sides the laterally curved end wings thereof abut against each other, the off-set flanges 5^c being arranged at opposite ends of the socket and each of the off-set flanges fitting around the end of the other socket section to provide a close joint. The flat middle portion of each of the socket sections is formed with a rearwardly extending tang 5^d. The lava block 2 is received between the two tangs 5^d of the respective socket sections and fits against the laterally curved ends 5^b of the socket sections, being held in position by means of fastening members or screws 6 which extend through the lava block and tangs.

The socket is shown as arranged back of a plate 7 with the mouth thereof projecting through a corresponding opening in the plate. The socket is supported by an L-shaped bracket 8, one of the arms of the bracket fitting against the plate 7 and being secured thereto by suitable fastening members 9, while the other arm of the bracket fits against the top of the socket and is engaged by the screws 6. These screws 6 thus perform the triple function of holding the lava block in position, securing the two socket sections together and fastening the socket to the supporting bracket.

As shown on the drawings the lava block is provided with three terminal pins 1 which project into the socket from the back thereof, although it will be understood that a lesser or a greater number of the terminal pins may be used as is necessary. Any conventional form of plug such as that indicated at B may be employed, said plug being adapted to slip over certain of the terminal pins and establish an electrical connection therewith.

As previously stated, the socket sections 5^a are similar and interchangeable, thereby avoiding the necessity of providing rights and lefts. A further important feature of the socket sections is that they are shaped so that each section can be bent into form at the same time that it is stamped out, thereby avoiding the expense of a second operation. The stamping and shaping of the socket sections is accomplished by one operation, and

for this reason the socket can be manufactured more economically than another socket which is designed so that after the stamping of the blank a second operation is required to bend and shape the same. This is an important consideration and enables the sockets to be very economically produced.

Having thus described my invention what I claim as new and desire to secure by Letters Patent is,

1. A terminal socket including complementary socket sections adapted to be fitted against each other from opposite directions, an insulating block, fastening members connecting the socket sections together and also engaging the insulating block; and terminal pins carried by the insulating block.
2. A terminal socket including complementary socket sections adapted to be fitted against each other from opposite directions, said socket sections being formed with tang portions, an insulating block received between the tang portions, fastening members extending through the tang portions and insulating block and serving both to secure the insulating block in position and fasten the socket sections together, and terminal pins carried by the insulating block.
3. A terminal socket including complementary socket sections adapted to be assembled from opposite directions and each comprising an intermediate plate having laterally bent end portions and a rearwardly projecting tang, an insulating block received between the tangs and fitting against the laterally bent end portions, fastening members extending through the tangs and insulating block and serving both to hold the insulating block in position and fasten the socket sections together, and terminal pins carried by the insulating block.
4. A terminal socket including similar and interchangeable complementary socket sections adapted to be assembled from opposite directions, each of the socket sections including a metal plate having laterally bent end portions and a rearwardly extending tang, an insulating block received between the tangs and abutting against the laterally bent end portions, fastening members extending through the tangs and insulating block and serving both to hold the insulating block in position and secure the socket sections together, and terminal pins carried by the insulating block.

5. A terminal socket including complementary sections adapted to be assembled from opposite directions, an insulating block, a supporting bracket, and a single set of fastening members extending through the supporting bracket, socket sections and insulating block to fasten the parts together, and terminal pins carried by the insulating block.

6. A terminal socket including a pair of similar and interchangeable complementary socket sections adapted to be assembled from opposite directions and formed with tang portions, an insulating block received between the tang portions, a supporting bracket having a portion fitting against one of the tang portions, a single set of fastening members extending through the supporting bracket, insulating block and tang portions of the socket sections, and terminal pins carried by the insulating block.

7. A terminal socket shell comprising a plug receiving body comprising sections having laterally deflected ends abutting and overlapping each other, a side of the shell being formed with a projecting tang, an insulated block abutting with an end portion of the shell, securing members between the tang and the insulating block, and terminal members carried by the insulating block.

8. A terminal socket including a body adapted to receive a plug, an insulating block carried by the body at one end thereof, said body being formed with a projecting tang at the end adjacent to said block, which tang overlaps the block at one side of the latter, securing means connecting the tang and the insulating block, and terminal pins mounted on the insulating block and terminating within the body aforesaid.

9. An electrical terminal plug-in socket comprising a shell open at its ends, said shell being formed by similar and interchangeable complementary sections, each formed of a sheet metal plate having laterally curved side portions, one of the side portions of each plate being provided with an offset flange and shoulder abutting against the straight side portion of the associated plate when the plates are assembled, the offset flanges then overlapping the joints, an insulating block, terminal pins carried by said insulating block, and fastening means for holding the parts together.

In testimony whereof I affix my signature.

HENRY A. ZIOLA.
